UNITED STATES PATENT OFFICE.

TRACY EVANS AND JOHN EVANS, OF RICHMOND, INDIANA.

DESIGN FOR A BIRD HOUSE.

Application filed October 21, 1925. Serial No. 15,215. Term of patent 7 years.

To all whom it may concern:

Be it known that we, TRACY EVANS and JOHN EVANS, citizens of the United States, residing at Richmond, in the county of Wayne and State of Indiana, have invented a certain new, original, and ornamental Design for Bird House, of which the following is a specification, reference being had to the accompanying drawing, forming part thereof.

The figure is a perspective view of a bird house, showing our new design.

We claim:

The ornamental design for a bird house as shown.

In testimony whereof we have hereunto set our hands this twelfth day of October, 1925.

TRACY EVANS.
JOHN EVANS.
